W. G. MOORE.
CLOTHES POUNDER AND WASHER.
APPLICATION FILED FEB. 24, 1913.

1,107,824.

Patented Aug. 18, 1914

UNITED STATES PATENT OFFICE.

WILLIAM GEORGE MOORE, OF CLEVELAND, OHIO.

CLOTHES POUNDER AND WASHER.

1,107,824.

Specification of Letters Patent. Patented Aug. 18, 1914.

Application filed February 24, 1913. Serial No. 750,121.

To all whom it may concern:

Be it known that I, WILLIAM GEORGE MOORE, a citizen of the United States, residing at Cleveland, in the county of Cuyahoga and State of Ohio, have invented certain new and useful Improvements in Clothes Pounders and Washers, of which the following is a specification.

My invention relates to a clothes pounder and washer, wherein a flexible diaphragm is arranged within a chamber and actuated by a plunger, the object being to compress the air and expel the water from the chamber during the pounding action, and to create a vacuum in said chamber, which causes the water to be drawn into it, thereby causing a greater agitation and mixing of the water and washing compound, and acceleration of the washing of the clothes.

Another object of the invention is to provide a pounder that is simple in construction, effective in operation and that can be manipulated in the manner common to hand clothes pounders.

With these objects in view, I will now describe my invention, reference being had to the accompanying drawings forming a part of the specification and in which—

Figure 1 is an elevation of the pounder and washer. Fig. 2 is a vertical section of the pounder, with the parts in the normal position. Fig. 3 is a similar section, with the plunger forced downward. Fig. 4 is a plan section on line 4—4, Fig. 1. Fig. 5 is an underside view of the pounder. Fig. 6 is an enlarged fragmentary view, showing the diaphragm attachment and guide post.

Similar characters of reference designate similar parts in the drawings and specification.

Referring now to the drawings, 1 represents a bell shaped body member, which is preferably stamped or formed out of sheet metal, and enameled or otherwise treated to prevent corrosion. The member 1 is open at the bottom 1^a, and also at the top 1^b. Around the top opening is a flange 1^c. Bonnets 2 and 3, provided with annular flanges 2^a and 3^a, are bolted or otherwise attached to the flange 1^c. The bonnet 2 is on the outside of the member 1 and the bonnet 3 depends inside of said member. A flexible diaphragm 4, preferably made of rubber, is clamped between the flanges 2^a and 1^c, and extends over the opening 1^b of the member 1. A grilled pounding member 5 is attached to

the bonnet 3, within the chamber of the member 1. An operating member or plunger 6 is attached to the diaphragm in the manner hereinafter described, and extends upward through the bonnet 2, and the ferrules 7 and 7^a, the latter, 7^a, being made fast to the plunger. Interposed between the two ferrules 7 and 7^a is a spring 8, the function of which is to return the plunger and diaphragm to their normal position when downward pressure has been relieved.

In order to form an air tight connection between the plunger 6 and the diaphragm 4, which is necessary, to obtain the desired result, and also to furnish a guide for the axial movement of the plunger, I provide a ferrule 9 on the lower end of the plunger. The ferrule 9 has a shoulder 9^a, and a reduced stem 9^b which extends through an opening in the center of the diaphragm. A jam nut 9^c is threaded onto the stem 9^b and clamps the diaphragm between said nut and the shoulder 9^a. The stem 9^b is hollow and adapted to slide on the guide post 10. The lower end of the plunger 6 is also bored to allow sufficient clearance for the guide post in the downward stroke. The bottom edge of the member 1 is provided with a rubber covering or shoe 1^e, which acts as a cushion for protecting the member and deadening noise when the pounder is used in shallow vessels.

It will be seen that when the mouth 1^a of the member 1 is submerged in water, and the plunger 6 forced downward, extending the diaphragm into the chamber 1^d, the air is compressed in the chamber and the water forced out, and when the pressure on the plunger is relieved, the diaphragm is distended upward, through the action of the spring 8, causing a partial vacuum in the chamber 1^d, into which the water rushes, to be forced out again by the downward action of the plunger.

In the foregoing specification, I have described a practical mechanism embodying my improvements, but I do not intend to be confined to the detailed construction described, only so far as it is necessary from the scope of the claims and the existing state of the art.

What I claim and desire to secure by Letters Patent is—

1. In a clothes washer the combination of a body, forming a chamber open at top and bottom; a flange around the top open-

ing; a flexible imperforate diaphragm clamped to said flange and entirely closing the top opening; means for extending said diaphragm into the chamber; means for automatically extending said diaphragm out of the chamber; and a stationary open-work member within said chamber, whereby the clothes to be washed are held down.

2. In a clothes washer the combination of 10 a body, forming a chamber open at top and bottom; a flange around the top opening; a flexible imperforate diaphragm clamped to said flange and entirely closing the top open-

ing; a plunger attached to said diaphragm for extending it into the chamber; means for automatically extending said diaphragm out of the chamber; means for guiding said plunger axially; and a stationary transverse open-work member within said chamber, whereby the clothes to be washed are held 20 down.

WILLIAM GEORGE MOORE.
